(57) **CLAIM**

The ornamental design for a core plate of electric rotating machine, as shown and described.

DESCRIPTION

FIG. 1 is a front elevational view of a core plate of electric rotating machine showing our new design;

FIG. 2 is a right side view thereof;

FIG. 3 is a left side view thereof;

FIG. 4 is a top plan view thereof;

FIG. 5 is a bottom plan view thereof; and,

FIG. 6 is a cross-sectional view taken along line 6—6 in FIG. 1.

1 Claim, 1 Drawing Sheet

FIG. 3

FIG. 6
